United States Patent Office

Des. 205,550

Patented August 16, 1966

205,550

JUG

Doyle J. Morgan, Toledo, Ohio, assignor to Owens-Illinois
Glass Company, Toledo, Ohio, a corporation of Ohio

Filed Mar. 22, 1965, Ser. No. 84,395

Term of patent 14 years

(Cl. D58—5)

FIG. 1

FIG. 3

FIG. 2

FIG. 4

FIGURE 1 is a front elevational view of a jug showing my new design;

FIGURE 2 is a back elevational view thereof;

FIGURE 3 is a side elevational view thereof; and

FIGURE 4 is a top elevational view thereof.

The side not shown is the same as the side shown. The characteristic features of this design reside in the configuration shown in full lines on the drawing.

I claim:

The ornamental design for a jug, substantially as shown and described.
